UNITED STATES PATENT OFFICE.

SPENCER HEATH, OF WASHINGTON, DISTRICT OF COLUMBIA, ASSIGNOR TO GYRO MOTOR COMPANY, OF WASHINGTON, DISTRICT OF COLUMBIA, A CORPORATION OF THE DISTRICT OF COLUMBIA.

ROTARY GAS-ENGINE.

1,112,905.

Specification of Letters Patent.

Patented Oct. 6, 1914.

Application filed September 8, 1911. Serial No. 648,369.

To all whom it may concern:

Be it known that I, SPENCER HEATH, a citizen of the United States, residing at Washington, in the District of Columbia, have invented certain new and useful Improvements in Rotary Gas-Engines, of which the following is a description, reference being had to the accompanying drawing and to the letters and figures of reference marked thereon.

The invention relates to new and useful improvements in gas engines, and more especially to the construction of the exhaust ports which are opened to give the initial relief to the expanded gases.

An object of the invention is to provide a plurality of exhaust ports which are so constructed and arranged that an initial relief of the expanded gases may be quickly accomplished, together with means for preventing the escape of the gases in the engine casing, through said exhaust ports on the outward stroke of the piston.

In the drawings which show by way of illustration one embodiment of the invention,—Figure 1 is a plan view of a rotary engine casing having a plurality of cylinders attached thereto, one of said cylinders being in section and the remainder of the cylinders being broken away, the cylinder in section having my improved auxiliary exhaust ports formed therein; Fig. 2 is a longitudinal section through a cylinder on a large scale, showing the piston in position for uncovering the auxiliary exhaust ports; Fig. 3 is a side elevation of a cylinder having my improvements applied thereto, and showing the means for closing the auxiliary exhaust port.

I have shown my invention as applied to a rotary gas engine which includes an engine casing 1 mounted on a shaft 2, so that said casing may rotate thereon. Said engine casing 1, as herein illustrated, supports seven cylinders 3. All of the cylinders are alike in construction, and, therefore, only one is shown in detail.

The cylinder 3 is provided with an opening 4 in its outer end, in which is seated a spider 5 having a seat for the main exhaust valve 6. This main exhaust valve may be controlled in any desirable way. Reciprocating within the cylinder is a piston 7 which is pivoted to a piston rod 8, connect-

ed to a crank of usual construction on the shaft 2. The piston 7 may be provided with an intake valve 9, so that the gases for operating the engine may be passed into the crank casing and through the inlet valves 9 into the cylinders. It will be obvious, however, from certain aspects of the invention, that the cylinders may be supplied with a fresh charge of gas in any of the well known ways.

In order that the cylinder may be quickly relieved of the expanded gases, I have provided a plurality of auxiliary or primary exhaust ports 10—that is, exhaust ports which are uncovered before the main exhaust port is opened to allow the first or initial relief of the expanded gases. The cylinder adjacent the end of the piston stroke is thickened as at 11, and said auxiliary exhaust ports are arranged in said thickened portion and are preferably inclined, so that the longitudinal axes thereof meet at a common point in the combustion chamber. By providing the thickened portion 11, I am able to increase the number of auxiliary ports over what has heretofore been used, without in any way weakening the cylinder at this point. By this increased number of auxiliary exhaust ports, I am able to very quickly relieve the cylinder of the expanded gases. Of course, after the initial relief of the gases, the remainder of the burnt gases are forced through the main exhaust valve 6. Furthermore, by the inclined exhaust port which is preferably circular in cross section, the opening of the exhaust port into the cylinder will be elliptical in shape, with the major axis of the ellipse extending longitudinally of the cylinder. While, therefore, the gases are quickly relieved through the number of exhaust ports, yet the gases will be gradually released in each exhaust port, and, therefore, the noise incident to the initial relief of the expanded gases is reduced to a minimum.

In a rotary gas engine having a number of cylinders, such as illustrated in Fig. 1, the length of the cylindrical portion of the piston is necessarily limited, for the reason that if said cylindrical portion extends into the casing upon the extreme inward stroke of the piston, it is liable to contact with the cylindrical portion of the piston in the next adjacent cylinder. It is not desirable

to increase the length of the cylinders so as to permit an increase in the length of the piston, and, therefore, it may be desirable in an engine of this type to allow the auxiliary exhaust ports to be uncovered by the pistons as they move outward to the extreme end of their stroke. It has been found desirable also to lubricate the piston by supplying lubricating oil thereto through the 10 crank casing. The centrifugal force will carry the lubricating oil out into the cylinders, and by the use of a cone-shaped guide 12, the oil will be properly directed to the wearing surfaces of the piston. However, 15 when an engine casing is provided with the usual auxiliary exhaust ports, which are uncovered by the piston as it moves to the outer end of its stroke, there is a loss of the lubricating oil through the auxiliary exhaust ports. As the oil is carried outward by centrifugal force, it will pass into these ports, and if the ports are arranged at right angles to the walls of the cylinder, it will creep outward through said ports. It is 20 consequently necessary to provide the ports with valves to prevent the loss of the lubricating oil. Furthermore, as the piston moves inward to uncover the exhaust ports, the lubricating oil in the ports will be blown 25 out and burnt with the escaping hot gases. By my construction, however, wherein the auxiliary exhaust ports are inclined relative to the wall of the cylinder, and also inclined so that any lubricant in said ports will be 30 carried by centrifugal force along the walls thereof into the cylinder, rather than out of the same, I am able to prevent the escape of any of the lubricant through the auxiliary ports without the use of any valves 35 for closing the same.

When the crank casing of the engine is used as a receiving chamber for the explosive gases which are led to the cylinder through the intake valve in the piston head, 45 and when the primary or auxiliary exhaust ports are uncovered by the outward movement of the piston, it is necessary to provide some means for closing the auxiliary or primary ports to prevent either the undue suction of air, or the escape of the explosive gases through these ports.

As shown in Fig. 1, the thickened portion 11 of the cylinder is formed with a shoulder 13, which shoulder lies in a plane cutting the 55 longitudinal axis of the cylinder substantially at right angles. The auxiliary exhaust ports 10 open in the center of the face of the shoulder 13.

A ring 14 is placed around the cylinder 60 and is adapted to rest against the shoulder 13. Said ring may be made in sections rigidly secured together to facilitate the placing of the same on the cylinder. This flat ring will close all of the auxiliary or primary exhaust ports when pressed against

the shoulder. The centrifugal force acting upon the ring when the engine is rotating, will yieldingly hold said ring against said shoulder and close said auxiliary exhaust ports. As soon, however, as the piston head 70 uncovers these exhaust ports on the inner stroke thereof, the expanding gases rushing through said exhaust ports will force the ring from its seat on the shoulder 13, and escape. When the piston head moves to the 75 other end of its stroke, the ring will be seated by centrifugal force and thereby prevent the drawing in of air through the crank casing on the suction stroke of the piston.

In order to hold the ring 14 on its seat 80 when the engine is being started, I have provided a plurality of supporting springs 15, which springs, as herein shown, are leaf shape, and are attached to the cylinder by suitable screws 16. The ring will rest on 85 said springs, which will yieldingly hold the same against its seat. It will be understood that in place of the leaf springs, any other suitable means may be provided for yieldingly holding the ring seated against the 90 shoulder 13 when the engine is being started.

It is obvious that minor changes in the details of construction and arrangement of parts may be made, without departing from the spirit of my invention, as set forth in 95 the appended claims.

Having thus described my invention, what I claim as new and desire to secure by Letters Patent, is:—

1. A rotary gas engine including in combination, a crank casing, a cylinder carried thereby, said cylinder being provided with a plurality of auxiliary exhaust ports extending through the wall of the cylinder at points adjacent the inner extreme throw of 105 the piston, a piston movable relative to said cylinder and adapted to uncover said auxiliary exhaust ports at each end of its stroke, means for supplying the combustion chamber of the cylinder with fuel gases from the 110 crank casing, and yielding means for closing said auxiliary exhaust ports to prevent air passing through the same to the crank casing.

2. A rotary gas engine including in combination, a crank casing, a cylinder carried thereby, said cylinder being provided with a plurality of auxiliary exhaust ports extending through the wall of the cylinder at points adjacent the inner extreme throw 115 of the piston, a piston movable relative to said cylinder and adapted to uncover said auxiliary exhaust ports at each end of its stroke, means for supplying the combination chamber of the cylinder with fuel 120 gases from the crank casing, and yielding means operated by centrifugal force incident to the rotation of the cylinder for normally closing said auxiliary exhaust ports.

3. A rotary gas engine including in com- 130

bination, a crank casing, a cylinder carried thereby, said cylinder being provided with a plurality of auxiliary exhaust ports extending through the wall of the cylinder at 5 points adjacent the inner extreme throw of the piston, a piston movable relative to said cylinder and adapted to uncover said auxiliary exhaust ports at each end of its stroke, means for supplying the combustion 10 chamber of the cylinder with fuel gases from the crank casing, said cylinder at the region of the auxiliary exhaust ports being thickened and formed with a shoulder, and a ring adapted to move outwardly on the 15 cylinder to engage said shoulder to close said auxiliary exhaust ports, and means for yieldingly holding said ring on said shoulder.

4. A rotary gas engine including in combination, a crank casing, a cylinder carried thereby, said cylinder being provided with a plurality of auxiliary exhaust ports extending through the wall of the cylinder at points adjacent the inner extreme throw of 25 the piston, a piston movable relative to said cylinder and adapted to uncover said auxiliary exhaust ports at each end of its stroke, means for supplying the combustion chamber of the cylinder with fuel gases 30 from the crank casing, said cylinder having a thickened portion forming a shoulder in the region of the auxiliary exhaust ports, and said auxiliary exhaust ports being inclined toward a common point within the 35 combustion chamber and opening through

the face of said shoulder, and a ring surrounding the cylinder and movable longitudinally thereon into engagement with said shoulder for closing said auxiliary ports. 40

5. A rotary gas engine including in combination, a crank casing, a cylinder carried thereby, said cylinder being provided with a plurality of auxiliary exhaust ports extending through the wall of the cylinder at 45 points adjacent the inner extreme throw of the piston, a piston movable relative to said cylinder and adapted to uncover said auxiliary exhaust ports at each end of its stroke, means for supplying the combustion 50 chamber of the cylinder with fuel gases from the crank casing, said cylinder having a thickened portion forming a shoulder in the region of the auxiliary exhaust ports, and said auxiliary exhaust ports being inclined toward a common point within the combustion chamber and opening through the face of said shoulder, a ring surrounding the cylinder and movable longitudinally 55 thereon into engagement with said shoulder for closing said auxiliary ports, and a spring for normally holding said ring against said shoulder. 60

In testimony whereof I affix my signature, in presence of two witnesses.

SPENCER HEATH.
